(57) **CLAIM**

The ornamental design for the diffusing evaporator for volatile substances, as shown and described.

DESCRIPTION

FIG. 1 is a front and side perspective view of a diffusing evaporator showing our new design;

FIG. 2 is a rear and side perspective view thereof;

FIG. 3 is a front plan view thereof;

FIG. 4 is a side view thereof, the opposite side view being the mirror image of FIG. 4;

FIG. 5 is a bottom view thereof;

FIG. 6 is a rear plan view thereof; and,

FIG. 7 is a top view thereof.
